REPAIR SOLE FOR RUBBER BOOTS OR SHOES

Filed April 5, 1927

UNITED STATES PATENT OFFICE.

ALEXANDER SZEKERES, OF TRENTON, NEW JERSEY.

REPAIR SOLE FOR RUBBER BOOTS OR SHOES.

Application filed April 5, 1927. Serial No. 181,138.

This invention relates to an improved repair sole for rubber boots or shoes, and has more particular reference to an improved article of manufacture of the above kind adapted to be applied over or upon the worn out sole of the boot or shoe to be repaired.

The primary object of the present invention is to provide a repair sole of the above kind which may be applied effectively in an expeditious manner, and which, when applied, will present a neat appearance.

A further object is to provide a repair sole of the above kind so formed as to be capable of effective attachment to a degree insuring against accidental detachment or the development of leaks.

Other objects will become apparent as the nature of the invention is better understood, and the same consists in the novel form, combination and arrangement of parts hereinafter more fully described, shown in the accompanying drawing and claimed.

In the drawing, wherein like reference characters indicate corresponding parts throughout the several views,

Figure 1 is a top plan view of a repair sole for rubber boots or shoes, constructed in accordance with the present invention;

Figure 2 is a longitudinal section taken substantially upon line 2-2 of Figure 1;

Figure 3 is an enlarged fragmentary transverse section taken substantially upon line 3-3 of Figure 1; and

Figure 4 is a perspective view of an over-shoe having a repair sole constructed in accordance with the present invention, applied thereto.

Referring more in detail to the drawing, the present article of manufacture or repair sole consists of a rubber or other resilient sole member 5 and an attaching member 6 also formed of rubber or other elastic material. The attaching member 6 consists of a thin sheet of rubber having a bottom portion 7 shaped to conform to the sole of the shoe to be repaired and of a size to extend across and slightly beyond the front and side edges of said sole of the shoe. The attaching member 6 further embodies a marginal flange 8 of upwardly and inwardly curved form as shown in Figure 3, said flange being integral with the bottom portion 7 and extending along the sides and around the front end of the latter as shown clearly in Figure 1.

The bottom portion 7 of the attaching

member is securely cemented upon the upper surface of the sole member 5, and the flange 8 is shaped to snugly fit over the sides and toe of the shoe upper. It is thus apparent that the repair sole is applied to the shoe by slipping the same rearwardly onto the forepart of the shoe, the upwardly and inwardly curved form of the flange 8 tending, in itself, to retain the repair sole in place upon the shoe. It is noted that the flange 8 is highly flexible because forming part of a thin yielding sheet of rubber, and thus, when the inner surfaces of the bottom part 7 and flange 8 are entirely coated with a cement, pressure may be brought to bear upon the outer surface of the flange 8 and the under surface of the sole 5 when the repair sole is operatively disposed upon the forepart of the shoe, thereby causing firm adhesion of the attaching member throughout the area of its inner surface to the worn sole and adjacent upper portion of the shoe so that an effective neat attachment of the repair sole is had. The neatness of appearance is further enhanced by tapering the rear free edges of the sole member and the bottom part 7 of the attaching member 6, in thickness, to a substantially feather edge as indicated generally at 9, and likewise tapering the flange 8 to a substantially feather free edge as indicated at 10.

In order to effect a most desirable repair of the shoe as well as a secure attachment of the repair sole, the bottom part 7 and sole member 5 are of such length as to extend rearwardly onto the forepart of the shoe shank 11 as indicated in Figure 4, the rear end portions of the sole member 5 and bottom part 7 being upwardly deflected or shaped to lie in contact with this forward part of the shoe shank as indicated at 12. The upward shaping of the rear end portions of the sole member 5 and bottom part 7 is of course more pronounced at the inner side than at the outer side as is the case with the usual shoe shank. Further, as shown in Figure 1, the rear end edge of the repair sole is disposed diagonally, the parts being extended rearwardly for a greater distance at the outer side of the repair sole than at the inner side thereof. This formation results in a neat appearing repair job when the present device is applied to the shoe, and the point of attachment at the rear is at a point where the shank 11 of the shoe is elevated or disposed to not contact with the

ground. In this way, a further guarding against the occurrence of leakage or accidental detachment is had.

As shown in the several views, the sole member 5 is preferably formed of such size so as to project slightly beyond the sides and front end of the attaching member 6 to preserve its actual characteristics of being a separate sole lift.

10 A repair sole constructed in accordance with the above has the inherent tendency to retain itself upon the shoe by reason of the formation of the flange 8, and when the device is cemented in place a neat and durable

15 construction is had.

What I claim as new is:—

As a new article of manufacture, a repair sole for rubber boots or shoes consisting of an attaching member formed from a piece of

20 thin flexible material and embodying a bot-

tom part adapted to extend across the bottom and beyond the edges of the sole to be repaired and having an integral upwardly and inwardly curved marginal attaching flange extending along its sides and around its forward end and a sole lift cemented to the under side of said bottom part of the attaching member, the attaching flange being proportioned to enclose the sole to be repaired and to overlie a portion of the shoe upper for completely hiding the original sole from view, the edge of the flange being feathered to merge into the upper and to eliminate the presence of a shoulder, and the repair sole being adapted to be adhesively retained in position on the sole and upper to be repaired.

In testimony whereof I affix my signature.

ALEXANDER SZEKERES.
